UNITED STATES PATENT OFFICE

CHARLES H. LITTLE, OF EAST CLEVELAND, OHIO

RULER

Application filed April 6, 1925. Serial No. 20,934.

This invention relates to rulers or drafting tools such as scales, straight edges, triangles, protractors and the like, and is an improvement over the rulers disclosed in my 5 prior application, Serial No. 431,537.

In general, it is the object of the present invention to provide certain improvements or features of construction which impart to the rulers the chief advantages of both 10 wooden and metal rulers as heretofore commonly employed, and at the same time to eliminate certain well-known disadvantages of both types. More particularly, it is the aim of the invention to provide rulers which 15 have substantially the lightness and the legibility and certain other desirable characteristics of wooden rulers, but do not possess the warping characteristic and lack of permanency and accuracy characteristic of 20 wooden rulers, but which also possess the stiffness, accuracy and permanency of metal rulers, but not their poor legibility, tendency to soil the drafting paper, and certain other undesirable features or characteristics of 25 metal rulers as heretofore employed.

Still further the invention aims to accomplish the above objects more effectively than in my prior Patents Nos. 1,274,291 and 1,274,292, granted July 30, 1918.

30 Still further objects are to provide a non-wooden and non-warping core, preferably a light, solid metal core, wholly enclosed in a non-metallic, preferably celluloidal covering formed and applied in a new and inexpensive manner, which will admit of the 35 rulers being constructed cheaply but accurately and otherwise satisfactorily, and so as to provide a celluloidal covering having distinct advantages over that in my Patent No. 40 1,274,292.

A still further object is to provide certain improvements in connection with graduated rulers, which improvements facilitate the use of such rulers by permitting exact measurements or dimensions to be laid out more 45 readily and quickly, and with less strain on the eyes, than if the graduations alone are relied on.

The above and other objects are attained 50 by my invention, which may be here sum-

marized as consisting in certain novel details of construction, and combinations and arrangements of parts, all of which will be described in the specification and set forth in the appended claims.

In the accompanying sheets of drawings wherein I have illustrated rulers in the form of a scale and straight edge embodying my invention in its preferred form, Fig. 1 is 55 a plan view with a portion broken away; having a metal core, wholly encased in a tightly fitting non-metallic covering, the core being formed and the covering being formed and applied in accordance with my invention; Fig. 2 is a cross-sectional view 60 of the same; Fig. 3 is a cross-sectional view through dies closed onto the ruler, which is also shown in cross-section, this view illustrating the preferred way in which the covering or shell is applied to the core so 65 as to wholly enclose the latter; Fig. 4 is a cross-sectional view of the solid metal core for the scale; Fig. 5 is a perspective view of a portion of the scale with one corner in 70 section to illustrate the homogeneous or 75 seamless character of the covering which is applied to the core; Fig. 6 is an enlarged view showing a portion of the scale partly in end elevation and partly in section to illustrate notches which may be applied in 80 the working edges of the scale and into which the point of the pencil may be placed by the draftsman so as to permit the desired dimensions to be marked on paper with more accuracy and speed than is the case if 85 graduations and characters alone are relied on; Fig. 7 is a fragmentary edge view of the same; Fig. 8 is a similar view illustrating a slight modification in the form of the notches and in their arrangement with respect to the graduations; Fig. 9 is a perspective and more or less diagrammatic view illustrating in separated fashion the two parts of the non-metallic shell and the 90 solid core of which the scale is composed; Fig. 10 is a plan view of a portion of the scale, the same being provided with a chuck-plate to adapt it for use in a drafting machine; Fig. 11 is a plan view of a straight edge embodying my invention; Fig. 12 is 95 100

a cross-sectional view of the same; Fig. 13 is a partial longitudinal sectional view of the same; Figs. 14 and 15 are respectively a transverse sectional view and a partial longitudinal sectional view, showing the parts which form the straight edge, separated as in Fig. 9; and Fig. 16 is a view similar to Fig. 5 showing a portion of the straight edge.

10 Referring now to the drawings, reference will first be made to the core or metallic part of the composite ruler. The shape of the core will depend, of course, upon the type or kind of ruler to which my invention is applied, but it is a characteristic of all my present improved rulers that the core is formed of solid metal, and in this respect it differs from the rulers of my prior patents, before referred to, wherein the core, for the 15 sake of lightness is formed of sheet metal and is hollow. To permit the use of a solid core which has the desired degree of stiffness and is sufficiently light in weight to answer the requirements, special metals or 20 alloys are necessary, and several of which may be employed. For example, I have used advantageously for this purpose, magnesium and a magnesium-aluminum alloy consisting chiefly of magnesium, and containing a 25 small percentage of aluminum, as for example, approximately 92% to 96% of magnesium and 8% to 4% of aluminum, or duralumin may be used advantageously. These metals or alloys not only have a sufficiently low specific gravity, but what is more 30 important, they can be drawn or extruded to the exact cross-sectional dimensions and to the desired shape that the core is to assume in the ruler, which shape, as already 35 stated, will depend upon the particular ruler 40 in which the core is to be employed. I prefer to produce the core in the desired shape by the drawing or extruding process, not only because of the relatively low cost of 45 this process, but a drawn or extruded core is peculiarly fitted for this purpose in view of the fact that in the process of forming it, it receives a skin or surface hardening which adds to the stiffness of the core, and furthermore, it is relieved of bending or internal 50 stresses which may, and generally do occur in machining.

In the case of the scale, the solid core 10 has a flat bottom 10^a, and a top having the 55 middle portions 10^b parallel with the bottom, and tapered portions 10^c leading from the top surface portion 10^b substantially, but not quite to the lower face 10^a, leaving narrow, flat edges of approximately one-sixty-fourth 60 of an inch (more or less) in width, which edges are straight and parallel for the entire length of the scale.

The core for the straight edge is somewhat differently shaped, as illustrated in 65 Figs. 11, 12 and 13, this core, designated 11,

which is, of course, also solid, and is formed in the same manner as the core of the scale, having parallel top and bottom faces which extend in parallel planes to the side edges which are formed square and parallel. The 70 straight edges are frequently of considerable length, and the thickness may be varied in accordance with the length of the straight edge, to provide increased stiffness if the same should be found desirable.

75 The core of either the scale or straight edge may be provided with tapped openings to accommodate screws 12 for securing to the finished ruler, chuck-plates 13 (see Fig. 10), these chuck-plates when employed, adapting the ruler for use with a drafting machine, although it is immaterial whether these openings are provided in the core before or after the enclosing covering is applied to it. This connection of the chuck-plate to the solid metal gives a substantial hold at the end of the ruler which practically does away with any slight motion at this point, this being especially desirable in long rulers or straight edges. It is understood also, that the chuck-plates will be omitted in the event that the ruler is intended to be used as a separate tool independently of the drafting machine.

90 After the core of the ruler is formed into the right length it is encased in a non-metallic covering or shell which entirely encloses the core, is tightly fitted thereon, and is mechanically held by the core against movement in any direction.

95 The shell or covering is preferably formed of sheet celluloid, or some other suitable nitroderivative of celluloid, or possibly of some other substance having certain well-known properties or characteristics of celluloid, i. e. which in its finished state is hard, smooth, easily movable over drafting paper, and will not soil the paper; which is tough in the sense that it will not chip off and can be flexed without liability of breakage or tearing; which has cohesive properties such that fine, smooth lines or characters can be formed therein, which undergoes shrinkage that will cause the covering to 100 everywhere maintain the initial tight gripping relationship between the core and cover and will retain permanently its shape and accuracy; and which for use in producing certain rulers such as straight edges can be 105 made in transparent form thereby providing transparent edges which are very desirable for straight edges. Inasmuch as celluloid, and particularly sheet celluloid has all these 110 properties and characteristics, and others which admirably adapt it for this use, sheet celluloid is the preferred material for this covering, and the word "celluloid" is used 115 in this specification as applicable to any material having the above characteristics, or a sufficient portion of them to adapt it for 120 125 130

this purpose, and which otherwise has no other characteristics which would render it unsuitable for the purpose.

In the application of the covering to the core it is an important feature of the invention that though initially the covering may be formed of several parts, a seamless covering is produced directly on the core, preferably by heat and pressure, the latter causing 10 a true welding of the parts and making a homogeneous unitary or monolithic covering which tightly grips and wholly encloses the core. In the case of the scale, the covering, which is designated as a whole by the reference character 14, is preferably formed of two pieces or strips of sheet celluloid consisting of a top piece 14^a, and a bottom piece 14^b, one of these pieces, in this instance the bottom piece 14^b, being provided with bent-up tabs 14^c to form the covering for the ends of the core.

After these pieces are blanked out from sheet celluloid, slightly longer and also slightly wider than the core which they are 25 to enclose, the two pieces with the core beneath them are placed between the heated dies of a press, and are subjected to severe pressure and to heat for a sufficient length of time to weld the two parts together and form 30 a one-piece or seamless covering or shell completely enclosing the core. Dies suitable for this purpose are indicated conventionally at 15 and 16 in Fig. 3, these dies, as shown, being hollow or having interior spaces 15^a and 35 16^a for the circulation of a heating medium.

The dies have a cavity corresponding to the shape of the ruler to be formed, with the result that pressure is exerted between all portions of the core and covering as well as 40 between the overlapping marginal portions of the pieces initially forming the covering, that is to say, outside of and along both longitudinal edges of the core, and outside of and along the ends of the core. The result 45 is that not only is a seamless covering or shell formed around the core, with the parts of the covering everywhere welded together along the longitudinal edges and across the ends, but the shell everywhere tightly engages the core so that the core and shell are 50 mechanically held together and the core holds the shell against movement in any direction. The shrinkage tendency of the celluloid cannot, therefore, have the effect of causing between the core and shell any relative movement which could to the slightest degree destroy or affect the accuracy of the device. The only effect of such shrinkage or shrinkage 55 tendency would be to cause the shell, if possible, to more tightly grip the core.

I may, if desired, coat the core, or parts of which the shell or covering is composed, or both, if desired, with a celluloid solvent to clean the celluloid, to facilitate the welding 60 operation and to enhance the close adherence

between the core and shell. However, the effect of this is largely to bring about the exclusion of air between the parts and prevent the pocketing or trapping of air as the pressure is applied.

It is a feature of the process described above, that the scales have thickened edge portions 14^a. This not only permits truing and refinishing in the event that the edges are nicked from use, but also has a further advantage in that the edges may be notched in a manner and for a purpose to be described presently and also improves the welding process. Additionally it should be noted that the edges are square and straight and parallel when the covering is applied by the above process. It might be here mentioned that the thickened edge portions and square edges, highly desirable in tools of this kind, are not attainable when the core is formed of sheet metal and the covering applied in liquid form as a coating.

The same method described above is utilized in forming celluloidal coverings for other forms of rulers, such as for the straight edge, illustrated in Figs. 11, 12, 13, 14, 15 and 16, where the covering is designated as a whole by the reference character 17.

In forming this covering, transparent sheet celluloid is employed so that lines and characters can be seen through the celluloid, or through those portions thereof which project beyond the sides and ends of the core 11, it being a feature of this process that the transparency or translucency of the celluloid is not adversely affected by the welding process which forms the parts into a tightly adhering, seamless shell in which the core is in effect embedded.

In forming the covering 17 I prefer to use six pieces, consisting of top and bottom strips 17^a and 17^b, which extend the full length of the straight edge, two longitudinally extending filler strips 17^c, which engage the longitudinal edges of the core 11 and are overlapped by the strips 17^a and 17^b, and two transverse end filler pieces 17^d which engage the ends of the core and are overlapped by the end portions of the top and bottom strips. These end pieces 17^d may extend across the ends of the straight edge from one side edge to the other, in which event they will abut against the ends of the longitudinal filler strips 17^c, or they may fit in between the ends of the latter, in which event they will have a length equal to the width of the core. The former arrangement is now preferred by me.

These parts are placed in properly assembled relation about the core and are subjected to heat and pressure between dies as in the instance first described, the dies having a cavity corresponding in shape to the finished straight edge, and the heat and pressure being continued for a sufficient length of time

to weld the parts into a more or less monolithic covering which wholly encloses and everywhere tightly grips the core to the same degree and in the same manner as in the case of the scale. If desired, the parts may be coated with a solvent for the purposes previously explained, prior to being subjected to heat and pressure between the dies of the press.

Reverting now to the solid character of the core of each of the several rulers, and to the process in general, I wish to emphasize the importance of the solid core not only as to its utility over a sheet-metal core in a finished ruler, but also in the successful practicing of the above described processes wherein pressure plays an important part in forming the covering. The solid core not only has the important advantage over a thin walled sheet-metal core such as shown in my prior patents that it is not susceptible to crushing in use, as by the elbow of the draftsman, or to buckling, but a solid core is essential to withstand the severe pressure used in welding together the parts of which the unitary covering is formed, and effectively resists whatever pressure may be necessary in the application of the graduations 18 and characters 19 on the scales or other rulers to which graduations and designating characters may be applied. In particular, the term "solid" is employed in describing the core to distinguish from a core such as is formed from relatively thin sheet metal and is hollow, as in my prior patents, but the term, as herein used, does not exclude a core which may be provided along its length with openings formed in the core in case extreme lightness is desired, as long as such a core has the necessary stiffness, solidarity, accuracy and distortion resisting qualities to answer the requirement. This leads to the consideration of some other important features of the present invention both in the article and method aspects thereof.

Ordinarily, graduations are cut in the celluloid by a graduating machine, and the characters are stamped therein, one at a time. The usual cutting and stamping processes may be carried out in forming my improved scales, and other graduated rulers, such as protractors, but the process utilized by me in forming the coverings admits of the application of the graduations and characters not only effectively but in a time-saving manner by an entirely new method, i. e. by molding the graduations and characters and also notches to be referred to into the celluloidal covering either by the same dies which form or weld together the parts thereof, in which event, one of the die members will be provided in cameo or relief with graduation and character forming parts which protrude from the face of the

die, and which in the covering forming process are pressed or embedded in the covering, or the graduations and characters may by suitable dies be simultaneously pressed into the covering in a separate operation subsequent to the cover forming operation.

The severe pressure incident to this method of applying characters and graduations is readily withstood by the use of a solid core.

Additionally, other depressions may be, and preferably are formed in the edge portions of my improved graduated rulers, such as scales, which depressions, as far as I am aware, are entirely new, when arranged substantially as shown and for the purpose to be described. These depressions may be molded into the ruler covering by the pressure incident to the process of forming the cover, or they may be cut in a subsequent operation.

The depressions referred to, are in the form of notches, indicated in Figs. 5, 6, 7 and 8, and provided on the working edges of the rulers, particularly graduated rulers, to receive the point of the pencil in laying off dimensions on paper. These notches, which are molded or cut in the thickened edge portions of the ruler, extend back on a diagonal from the face of the edge, and they may be square in outline, as indicated at 20, or they may be triangular, as indicated at 20^a in Fig. 8. Furthermore, they are preferably employed in conjunction with the graduations 18, and they may be provided opposite and below all the graduations, as indicated in Fig. 7, or they may occur also between the graduations, in which event fewer graduations may be employed.

The purpose of these notches is to facilitate the laying off of dimensions as above stated, by acting as centers or positive locating points for the draftsman's pencil, which can be moved along the edge of the ruler and dropped into a notch beneath a given graduation, or between two adjacent graduations, so that the draftsman is enabled to locate on the drawing paper the position of the dimension point much more quickly and readily than if he were obliged to rely on the graduations alone.

These notches do not extend in height across the entire face of the edge of the ruler, but there is left above the notches an unbroken or smooth surface along which the pencil can be moved in the usual manner, and to find or locate a particular dimension point it is only necessary for the draftsman to tip his pencil P forwardly, when it is adjacent the proper notch, in the manner indicated in Fig. 6, in which event the pencil point will find its way or drop into the notch which accurately locates the dimension point. In this manner lines of given lengths or dimensions can be marked on the paper

with extreme accuracy, extraordinary speed, and with relatively little attention on the part of the draftsman.

By placing the notches between, as well as opposite the graduations, part of the graduations can be eliminated. For instance, a scale may be graduated to sixteenths of an inch, and notches cut to thirty-seconds of an inch. It is then very easy to work to thirty-seconds with a scale that only reads to sixteenths. A scale of this kind is much easier on the eyes and more quickly read. Poor lighting is therefore not so bothersome, and eye-strain is greatly reduced. I might add that I find that notches one-sixty-fourth of an inch in width answer the requirements very effectively, and that the pencil will find its way or drop into the notches more readily if the upright corners forming the sides 20 of the notches are slightly rounded off.

One other feature remains to be explained, and that has to do with the equalization of the tension or pull exerted by the celluloidal covering on opposite sides of the ruler when such sides, as the top and bottom of a scale, are unsymmetrical, i. e., are not similarly disposed from edge to edge. Inasmuch as portions of the top of the scale are beveled or tapered down toward the longitudinal edges, I find that the tension along the top of the scale, due to the pull created by the shrinking tendency of the celluloid is less than that along the bottom of the scale, which fact would, unless compensated for, cause a bowing of the scale. This, I find can be obviated entirely by making the celluloid strip forming the top of the scale, somewhat thicker than the strip forming the bottom. I find that by making the top strip approximately five thousandths of an inch or about 20% thicker than the bottom strip, the stresses along the top and bottom of the scale are exactly balanced. It is unnecessary to employ this expedient in producing the straight edges, for the top and bottom portions of the covering or shell are symmetrical, so that the stresses are balanced when top and bottom strips of equal thickness are employed.

By way of conclusion I might sum up the advantages inherent in, or derived from the use of rulers formed in accordance with the present invention as compared with the rulers heretofore used, and particularly the ordinary wooden and metal rulers.

1. *Accuracy.*—The edges remain straight and parallel, which is not true of rulers having a wooden base, because of the latter's tendency to warp. The graduated scales hold permanently their overall graduated length, whereas with wooden scales having graduated celluloid strips cemented thereto, tests show a slight shrinkage.

2. *Legibility.*—Scales formed in accordance with my invention have the permanency

and accuracy of metal scales, but can be read much more quickly and easily.

3. *Permanency of finish.*—The scales which are preferably covered with dull white celluloid have a finish which is pleasing and easy on the eye, and is much more durable than that on metal scales and scales having a wooden base, since in time the finish wears off in places from both wood and metal.

4. *Cleanliness.*—The rulers are particularly cleanly due to the inherently cleanly nature of compressed sheet celluloid, and due to their light weight.

5. *Lightness.*—My improved rulers are extremely light in weight, notwithstanding the fact that they have solid metal cores, and this makes them easy to handle, easy to place at the desired point on the drawing, and there is therefore less tendency for the rulers to grind or rub dirt into the drawing paper when they are moved over it. Light weight metals have heretofore not been satisfactory for rulers because they have either soiled the drawing unduly, or have finishes that would soon wear off.

6. *Agreeable to the touch.*—These rulers are especially agreeable to the touch, partially because celluloid is not a good conductor of heat and partially on account of the smooth, cleanly surface of celluloid. A metal scale because it is a good conductor of heat is not pleasing to the touch.

7. *Durability.*—These rulers are far more durable than either metal rulers or those having a wooden base. The celluloid will not loosen at any point nor chip off, and it provides a permanent finish for the metal core, while the latter provides permanent accuracy for the celluloid edges in the way of straightness and parallelism, and permanent accuracy for the graduations.

8. *Efficiency.*—Not only do these scales and other rulers formed in accordance with my invention have great utility because of their lightness, permanency, accuracy and legibility and for other reasons heretofore mentioned, but the notches provided along the edges of the scales or other graduated rulers greatly enhance the speed and ease with which drawings can be made which require accurately marked off dimensions, and they reduce eye-strain, as already pointed out. The fact that the ruler has a thickened edge which permits the notches to be formed with a smooth surface above it as well as permitting truing in the event the edge is nicked is a decided advantage over rulers having a non-thickened edge as in my prior patents.

9. *Low cost of manufacture.*—My improved rulers, despite their excellency, can be produced inexpensively, since the heat and pressure and dies used in welding the tightly fitting celluloidal cover and in producing with the core a light but solid mass

permits the rapid production of uniformly accurate scales and other rulers with a minimum of wastage. On the contrary, in the production of wooden rulers, the wastage is 5 very high because of warping. Additionally the cost of production is greatly reduced when the graduations, characters and notches are molded in the celluloid, particularly during the cover forming process.

10 While I have illustrated only scales and straight edges, my invention may be utilized also in the production of still other rulers, such as those mentioned in the early part of the specification, and while I have 15 described these rulers in their preferred form, and have specified the preferred materials, and the preferred process of producing the rulers, I do not desire to be confined to the exact details, steps of the 20 method, or materials specified, but aim in my claims to cover all modifications which do not involve a departure from the spirit and scope of my invention in its broadest aspects.

25 The herein disclosed process of forming the rulers, including the molding of the graduations, characters and notches, is claimed in a divisional application Serial No. 370,220 filed June 12, 1929.

30 I claim:

1. A ruler comprising a core and a unitary seamless welded celluloidal covering completely and tightly enclosing the core including the ends and held from substantial movement thereon in any direction, said covering having a ruling edge held straight by the core.
2. A ruler having unsymmetrical opposite sides and provided with a celluloidal 40 covering thicker on one side than on another to balance the shrinkage stresses.
3. A ruler comprising a core having unsymmetrical opposite sides, and a celluloidal covering tightly enclosing the core and 45 thicker on one side than on the other to balance the shrinkage stresses.
4. A ruler comprising a metal core and a molded unitary seamless covering completely and tightly enclosing the core including the ends, and having a ruling edge held straight by the core.
5. A ruler comprising a metal core and a molded seamless unitary celluloidal covering completely and tightly enclosing the core including the ends, and having a ruling edge held straight by the core.
6. A ruler having graduations extending down to its edge and notches formed along the bottom of the edge in definite spaced 60 relation to the graduations, the intermediate portion of the edge between the ends of the graduations and the notches being smooth.

In testimony whereof, I hereunto affix my signature.

65 CHARLES H. LITTLE.
